DESIGN FOR A WATCH BRACELET

Eugen Prestinari, Summit, N. J., assignor to Gemex Company, Newark, N. J., a corporation of New Jersey

Application February 4, 1938, Serial No. 74,877

Term of patent 3½ years

To all whom it may concern:

Be it known that I, Eugen Prestinari, a citizen of the United States and a resident of Summit, in the county of Union, State of New Jersey, have invented a new, original, and ornamental Design for a Watch Bracelet, of which the following is a specification, reference being had to the accompanying drawing, forming a part thereof.

In the drawing,

Figure 2 is a side elevational view of the bracelet shown in Figure 1.

The drawing discloses one-half of the watch bracelet, the other half being a duplication of that shown.

I claim:

The ornamental design for a watch bracelet as shown and described.

EUGEN PRESTINARI.
